DESIGN FOR A LIGHTING FIXTURE

Thomas A. Carter, Jr., Grand Rapids, Mich., assignor to Grand Rapids Store Equipment Company, Grand Rapids, Mich., a corporation of Michigan

Application September 8, 1941, Serial No. 103,217

Term of patent 7 years

To all whom it may concern:

Be it known that I, Thomas A. Carter, Jr., a citizen of the United States, residing at Grand Rapids, in the county of Kent and State of Michigan, have invented a new, original, and ornamental Design for a Lighting Fixture, of which the following is a specification, reference being had to the accompanying drawing, forming part thereof.

Fig. 1 is a perspective view of a lighting fixture showing my new design, and

Fig. 2 is a transverse cross section of the same taken along the line 2—2 of Fig. 1.

The essential features of my design reside in those portions shown in solid lines on the drawing.

I claim:

The ornamental design for a lighting fixture, substantially as shown and described.

THOMAS A. CARTER, JR.
